CARBURETOR

Scott F. Hunt, Detroit, Mich., assignor to Bendix
Aviation Corporation, South Bend, Ind., a cor-
poration of Delaware

Application January 16, 1933, Serial No. 652,047

4 Claims. (Cl. 123—119)

This invention relates to carburetors, more especially to automatic choke valve control mechanisms therefor, and has for its principal object the provision of an improved thermostat control for a mechanism of this kind.

Internal combustion engines using liquid fuel require a richer mixture when the engine is cold than when it is hot. Carburetors for forming this fuel mixture are provided with a control valve, usually an air supply regulating valve or choke, which is adjustable to regulate the richness of the mixture. Certain prior art devices, of which the copending application of S. F. Hunt, Serial No. 653,518, filed January 25, 1933, is an example, provide a control mechanism for addition to or incorporation in the carburetor to automatically control the choke valve to produce a mixture varying in richness inversely as the engine temperature. This control is regulated by a thermostat which is usually mounted in juxtaposition to the exhaust manifold of the engine and heated thereby. The automatic control device may be locked in operated position when the engine is at normal operating temperature, so that the mixture then delivered to the engine is regulated by the carburetor adjustments rather than by the choke valve.

In certain instances the thermostat will be heated too rapidly by heat radiated directly from the manifold when the engine is started, with the result that the richness of the mixture will be graded down too rapidly. The exhaust manifold, being composed of relatively thin metal, cools down rapidly and the thermostat may also cool down too rapidly when the engine is stopped or run at idling speed, with the result that, when the engine is restarted before it has had time to get cold or is brought up to a high speed after idling, the mixture delivered to it will be too rich.

The present invention teaches improving the operation of the prior art devices by absorbing a quantity of heat from the manifold during the warming up period of the engine and dissipating that heat during the cooling down period to alter the operations of the thermostat, and provides means for accomplishing this result.

My invention will be best understood from the accompanying detailed description of a preferred embodiment of it, reference being had to the accompanying drawing in which:

Figure 1 is an elevational view of a carburetor and control mechanism therefor;

Figure 2 is an end elevational view of Figure 1, partly in section along the line 2—2 of Figure 1, looking in the direction of the arrows;

Figures 3 and 4 are views similar to Figure 2 but showing modified forms of the invention; and

Figure 5 is a detail view of a spacing collar.

Referring now to the drawing in more detail, the carburetor 10 is a down draft plain tube carburetor having a choke valve 12 located in the air intake horn 13, and a throttle 14 controlling the mixing chamber 15. The casing is flanged at 16 to facilitate mounting the carburetor on the intake manifold 17 of the engine. The choke valve 12 is fixed upon the manifold adjacent to the carburetor. It is to be understood that the specific arrangement shown is shown by way of example only as the invention may be applied to other types of carburetors and the control mechanism may be incorporated in the carburetor structure, within the teachings of the present invention.

The choke valve 12 is mounted by a shaft 22 which carries a lever 24 through which the choke is moved. The free end of the lever 24 carries a rod 26, pivotally secured thereto, and the other end of this rod is pivoted to a lever 28 that is fixed upon a thermostat shaft 30. The choke valve 12 is of the unbalanced type, that is to say, pressure difference between its faces tends to open the valve. This movement of the valve is opposed by the tension of the thermostat 32, which tension decreases as the temperature increases. The throttle lever 14 may, if desired, be connected to the control unit 20 by a rod 33, as disclosed in the Hunt application above referred to.

The thermostat 32 is fixed at one end to the shaft 30 and at the other end to a casing 34 by a pin 36. The casing 34 is open faced and is mounted concentrically of the shaft 30 on a boss 38 which projects from the housing of the control unit 20. The casing 34 is rotatable upon the boss to adjust the tension of the thermostat, and is held in place by a suitable clamp and screw indicated at 40.

The control mechanism is located so as to bring the open face of the casing 34 opposite the exhaust manifold 42, but at some distance therefrom. The intervening space is filled by a heat absorbing medium 44 shown as a block of metal secured to the manifold by bolts 46. A soft metal gasket 48, preferably copper, is interposed between the block 44 and the manifold, and as the bolts are drawn up tight, the soft gasket will be forced into the irregularities of the surfaces with which it is in contact to form a good heat conducting connection between the

parts. The edge of the casing 34 which surrounds the open face thereof is abutted against the free face of the block 44 and serves with it to enclose the thermostat. The block 44 is preferably composed of cast iron, although other metal may be used if desired. The block has a large mass and is capable of storing a large quantity of heat.

In the operation of the device, hot gases passing through the exhaust manifold 42 heat the walls thereof. The heat is conveyed by conduction through the gasket 48 into the block 44 to raise the temperature thereof, but since there is a large mass of metal in the block, it will heat up slowly. As soon as block 44 becomes heated through, heat is radiated therefrom through the air surrounding thermostat 32 to heat up that element and cause it to lessen the tension by which valve 12 is biased towards its closed position. The delay occasioned by the heating of block 44 allows the engine to warm up sufficiently, to enable it to operate on the lean mixture produced with the valve 12 wide open, by the time thermostat 32 has been heated sufficiently to permit the valve to be fully opened.

When the engine is stopped and there are no hot gases in the manifold 42 the mass of metal in block 44 will cause it to cool down more slowly than the walls of the exhaust manifold. Thermostat 32 is maintained warm for a longer time after the engine has been stopped, so that if it is restarted before it has had a chance to cool down to atmospheric temperature, the thermostat will be above atmospheric temperature and the mixture will be maintained at more nearly correct richness. By properly proportioning the mass of the block 44 to the tension of the thermostat, the cooling down time and heating up time of the thermostat can be lengthened sufficiently to insure delivery of a proper mixture to the engine at all times.

If desired the block 44 may be cast as an integral part of the manifold of the engine. It is preferable, however, to form the block as a separate piece to be attached as shown, since it may then be made from metal having heat characteristics best fitted to the particular needs and without regard to the material from which the manifold is made. The gasket 48, specified as being composed of copper, may be of other soft metals or of a heat insulating material such as asbestos. Such a material will greatly retard the heating up of the block, but will have very little effect on the cooling of it.

In the modification shown in Figure 3, the mass of metal is replaced by a cup 50 which is secured to the exhaust manifold by screws 52 and which abuts the casing 34 in the manner shown. This arrangement results in a body of air being retained between the exhaust manifold and the thermostat, which air acts to some extent as a heat reservoir and to some extent as a heat insulation between the manifold and thermostat. The edges of the cup 50 and casing 34 may, if desired, be machined to present accurately registering faces which form a substantially air-tight seal, so that heat will be transferred to the thermostat by radiation, conduction and convection.

In the modification shown in Figures 4 and 5, somewhat the same type of heat reservoir is

formed by a collar 54 which is adjustably secured to the casing 34 by means of a screw and clamp arrangement 56. Where the distance between the control unit 20 and the exhaust manifold of different cars varies considerably, the air reservoir may be kept practically air tight by moving collar 54 into contact with the exhaust manifold and then tightening the clamp 56.

While I have shown my invention by describing a preferred form of it, I have done so by way of example only and do not regard the invention as limited thereby as I am aware that modifications may be made.

I claim:

1. The combination with an internal combustion engine equipped with an exhaust pipe, a carburetor having an induction passage, a choke valve mounted in the induction passage, thermodynamic means urging the choke valve toward closed position when cold, means comprising a relatively thick metallic block positioned between the exhaust pipe and the thermostat and a heat absorbing gasket between the exhaust pipe and the block to retard the flow of heat to and from the thermostat, said means having one surface adapted to partially enclose the thermostat, and a casing cooperating with said surface to completely enclose the thermostat to prevent the escape of fluid from the space surrounding the thermostat.

2. The combination with an internal combustion engine having an exhaust manifold and a carburetor, a carburetor control mechanism comprising a thermostat positioned adjacent to the exhaust manifold, heat absorbing means including a heat absorbing metallic block and a compressible gasket positioned between the thermostat and the exhaust manifold for delaying the heating and cooling of the thermostat as the manifold is heated and cooled, and a casing including a surface of the metallic block completely enclosing the thermostat.

3. The combination with an internal combustion engine having an exhaust manifold and a carburetor, of a carburetor control mechanism comprising a thermostat, a block of metal interposed between the thermostat and the manifold and out of contact with the thermostat, a soft gasket interposed between the block and exhaust manifold, and means for drawing the block into intimate contact with the gasket and the gasket with the exhaust manifold and for holding the block on the exhaust manifold to absorb heat therefrom during the warming up period of the engine, and a casing including a surface of the block of metal surrounding the thermostat.

4. The combination with an internal combustion engine having an exhaust manifold and a carburetor, a carburetor control mechanism comprising a thermostat and an unbalanced choke valve, connecting means between the choke valve and the thermostat, heat absorbing means including a metallic block and a resilient gasket positioned between the thermostat and the exhaust manifold for delaying the heating and cooling of the thermostat as the manifold is heated and cooled, and a casing including a surface of the metallic block completely enclosing the thermostat.
